CLAIM

The ornamental design for a spraying head for dosing and dispensing device, as shown and described.

DESCRIPTION

1.-2. Spraying head for dosing and dispensing device
FIG. 1.1 : Perspective view of a first embodiment of the spray head.

FIG. 1.2 : Left view of a first embodiment of the spray head.

FIG. 1.3: Right view of a first embodiment of the spray head.

FIG. 1.4 : Front view of a first embodiment of the spray head.

FIG. 1.5: Back view of a first embodiment of the spray head.

FIG. 1.6:Top view of a first embodiment of the spray head.

FIG. 2.1 : Perspective view of a second embodiment of the spray head.

FIG. 2.2: Left view of a second embodiment of the spray head.

FIG. 2.3: Right view of a second embodiment of the spray head.

FIG. 2.4: Front view of a second embodiment of the spray head.

FIG. 2.5: Back view of a second embodiment of the spray head.

FIG. 2.6: Top view of a second embodiment of the spray head.
